UNITED STATES PATENT OFFICE.

BARNES NEVILLE WALLIS, OF WESTMINSTER, LONDON, ENGLAND, ASSIGNOR TO AIRSHIP GUARANTEE COMPANY, LIMITED, OF WESTMINSTER, ENGLAND, A BRITISH COMPANY.

RIGID AIRSHIP.

Application filed January 24, 1925, Serial No. 4,504, and in Great Britain January 26, 1924.

This invention relates to rigid airships, the chief objects being to provide improved forms of transverse frames and longitudinal inmembers; to dispense with the usual 5 automatic gas valve discharge trunks; to produce an airship in which the main loads, such as the passenger and cargo cars, can be suspended from the sides thereof instead of being located along the keel as is customary; 10 to provide means for placing the said cars in communication with one another, and to establish an easy means of communication between the nose and stern of the airship.

In rigid airships of the Zeppelin type the 15 internal gas pressure acting radially outwards is usually borne by longitudinal girders and main transverse frame members constituted by interconnected diamond-shaped trusses lying in one plane, a large 20 number of transverse bracing and lift wires being also employed. In order that the side loading may not be excessive, a very large number of longitudinal girders are required which have little lateral stiffness, and the 25 use of intermediate transverse frame members, in addition to the main transverse frame members is rendered necessary. A complicated structure is, therefore, produced, the parts of which are exposed to 30 complex stresses which it is difficult to calculate or estimate. Moreover, the use of internal transverse bracing, which is also rendered necessary, is undesirable, because, in the event of one of the gas bags becoming 35 deflated, the contiguous bag or bags, protrude or tend to protrude laterally into the space formerly occupied by the deflated bag, thus bringing considerable end pressure to bear on the wire bracing and setting up 40 stresses which interfere with the strength and stability of the transverse frames.

According to one feature of the present invention the transverse frames are constituted by built-up space frame girders or 45 by members which occupy more than a single plane. In the case of space frame girders the latter may be of triangular cross section, the apex of the triangle being preferably directed towards the interior of the 50 ship, and the wires of the networks which enclose the gas bags being preferably connected to the transverse frames at or towards the out-turned base of the triangle. The triangulated frame members may be built

up from three ring-like members, conforming in shape to the external shape of the airship, each of which members may be itself of triangular or other space frame cross section and the parts being connected together by bracing wires and struts. 55

In lieu of making the transverse frames of triangular cross section they may be of any other space frame or box-like configuration, e. g. rectangular, circular, or polygonal in cross section, or else they may be constituted by a pair of polygonal rings connected together by bracing wires and struts. 60

Owing to the strength of a built-up space frame as compared with existing forms of transverse frames, the internal structure is 70 simplified as the use of internal bracing wires may be dispensed with or reduced, while an airship having fewer polygonal sides than is customary can be produced.

The aforesaid space frames are preferably employed in conjunction with the improved form of network described in the co-pending United States patent application No. 4,161 whereby the load is transferred to the frames as a tangential component and tangential loading can be resorted to and the loads slung from the sides of the airship where the maximum lifts are obtained; where this improved form of network is employed the use of intermediate 80 frame members is also rendered unnecessary. 85

In rigid airships the gas pressure of the balloonettes or gas bags is usually borne by longitudinal girders disposed between transverse frames which lie in a single plane, the girders being usually composed of sections which are riveted or otherwise attached at their ends to the transverse frames. This arrangement is open to the disadvantage 90 that the strength of each girder section owing to the fact that it is located between a pair of transverse frames which lie in a single plane is only that of a so-called pin-joint strut. 95

According to another feature of the present invention and in cases where the transverse frames are constituted by built-up space frame girders, part of the longitudinal frame, or short rigid struts of any suitable shape or section forming part of the longitudinal frame is or built into or otherwise rigidly connected to, each transverse frame. The longitudinal girder is thus 100 105

given a solid foundation in the built-up space frame and is supported at two points thus giving the longitudinal girders at the points where they join the transverse frames 5 the increased strength of struts of the built-in type. Intermediate struts or girder sections are provided and located between the ends of the embedded struts and rigidly connected thereto in any convenient manner.

10 According to a further feature of the present invention the intermediate struts or girder sections are connected in a detachable manner to those parts of the longitudinal girder or to the ends of the struts which 15 are embedded in the transverse frames, for example by means of flanges and bolts, or by pins, so that in the event of any girder section being damaged or requiring to be removed it can be readily detached and 20 afterwards replaced without interfering with the other sections of the longitudinal girders.

At the present time it is customary to provide the gas bags of rigid airships with automatic valve discharge trunks for the hydrogen, said trunks being usually constituted by fabric piping communicating with a discharge hood.

According to another feature of the present invention and in cases where the airship 30 is provided with transverse frames which are of box-like formation, and between which the contiguous gas bags are located, the flexible wires or the like comprising the network which encloses the gas bags are attached 35 to the outer edges of the said box-like frames so that the box-like transverse frames themselves provide an enclosed trunk-like passage or pipe. Gas valves are provided at the sides of the gas bags and 40 situated at a suitable height above the bottom of the bag, said valves being arranged to discharge automatically into the trunk-like passage or pipe formed by the box-like transverse frames, the gas which enters the 45 frames from the gas bags being adapted to escape from a hood situated for example at the top of the airship.

Consequently the use of the usual special discharge trunks is dispensed with and the 50 construction of the airship lightened and cheapened.

In airships of the Zeppelin or like types the cars or coaches for the accommodation of the passengers and cargo are usually 55 situated along the keel, and it has been proposed to establish communication between the passenger cars and an entrance at the nose of the airship by means of a passage which extends from the nose to the keel of 60 the ship. This arrangement, however, possesses the disadvantage that the passengers have to descend or ascend a very steep ladder or staircase when entering the coaches or 65 leaving the airship.

According to another feature of the pres-

ent invention the passenger cars are located at the sides of the airship and communication between the cars as also the nose and stern of the airship is established by means of corridors or gangways located on each 70 side of the airship in the space already existing between the inner framework and the outer cover, the corridors or gangways being suspended, after the manner of a suspension bridge, from supports or catenaries, the ends of each catenary being preferably connected to contiguous transverse frames. The corridors or gangways may be made in sections suitably connected together, and 75 may have a rigid floor, to which slings from the catenaries may be connected so as to dispense with the use of side girders, and thereby reduce weight. Radius rods or the like are provided and disposed between the gangways and the inner framework and the 80 outer cover of the airship so as to prevent 85 swinging of the suspended gangways.

As the suspended gangways can be located at or about the plane of the passenger cars at the sides of the ship, the use of very 90 steep staircases is avoided, while in cases where the airship is also provided with transverse frames which are of space frame construction, communication between the 95 cars on each side of the ship can be established by means of staircases located within the box-like transverse frames.

This arrangement of staircase in the transverse frames has the advantage that the 100 restaurant, lounges, kitchens, etc. can be located on the cars on one side of the airship, while the sleeping quarters for the passengers can be located on the other side of the airship, and ready access obtained from one car, or set of cars to the other through 105 the aforesaid permanent staircase in the transverse frames.

The space at the nose of the airship up to the first transverse frame may be fitted up 110 as an observation car or saloon, embarkation doors being provided leading to the exterior together with doors leading from the saloon to the aforesaid gangways.

In order that the said invention may be 115 clearly understood and readily carried into effect the same will now be described more fully with reference to the accompanying drawings which show more or less diagrammatically various parts of an airship embodying different features of the present 120 invention and in which:—

Figure 1 is a transverse section.

Figure 2 is a longitudinal section showing a gas bag in position between a pair of contiguous transverse frames.

Figure 3 is an elevation of part of the transverse frame showing on an enlarged scale two contiguous built-up struts.

Figure 4 is a plan showing on an enlarged scale part of one of the main longitudinal

girders and the contiguous portions of the transverse frame.

Figure 5 is a section taken on the line 5—5 of Figure 3.

5 Figure 6 is a section taken on the line 6—6 of Figure 4.

10 Figure 7 is an elevation showing in dotted lines the approximate position of the suspended gangway by which communication is established between the nose and stern of the airship.

15 Figure 8 illustrates the lower half of a modified construction of transverse frame and shows diagrammatically one of the transverse staircases by which communication is established between the passenger cars on each side of the airship.

20 Figure 9 shows the upper half of one of the transverse frames and indicates diagrammatically the approximate position of the suspended side gangways by which communication is established between the nose and stern of the airship, as also the gas valves and trunks.

25 Fig. 10 is a sectional view showing diagrammatically the position of the passenger cars.

A, A are the transverse frames; B, B are the longitudinal girders; C is one of the gas bags; D is the suspended gangway, and d, d are the catenaries, the ends of which are connected to the transverse frames, and from which the gangway D is suspended. E is the staircase located within the box-like transverse frame A by which communication is established between the passenger cars F, F, of Fig. 10, the latter being suspended from the framework by members F', F'' and located approximately at the 30 position shown in Fig. 7. The suspended side gangways D, D are shown at Figure 9 on an enlarged scale and located outside the outer cover; in practice, however, they will be located between the transverse frame A and the outer cover G as shown at Figure 8. G is the trunk or passage in the upper half of each box-like transverse frame through which hydrogen escapes by means of valves g', g' to the hoods g, g at the top of the airship. The lower end of each trunk is sealed at the joint g².

The method of constructing the transverse and longitudinal frames is shown more clearly at Figures 3, 4, 5 and 6. The frames A, A are triangular in cross section, and in the example shown comprise an upper member or girder a which is itself of triangular cross section, and two rectangular box-like girders a', a' at the lower end thereof. The box-like girders are of varying cross section as shown at Figures 3 and 4 and are built up from four hollow tubes a⁶, a⁶. The side and bottom members a³, a⁴, are also constituted by truss girders of triangular cross section.

Each longitudinal girder B is of triangular cross section and the apex girder b³ and base girders b², b² may also be constituted by built-up space frame girders of triangular cross section. At the points where the girder B meets the transverse frame A a pair of short rigid struts b, b' are provided which constitute extensions of the parts b², b² of the longitudinal girders and are built into the transverse frames so as to give the longitudinal girders a solid foundation therein. A third strut or built-in portion b⁵ is located between the rectangular members a⁶, a⁶ which form part of the transverse frames and connected thereto in any suitable manner. It is preferred, however, to connect the struts b', b' to the parts b², b² of the longitudinal girders, as also to connect the strut b⁵ to the rectangular portions a⁶, a⁶ of the transverse frames by means of pin joints b⁴, b⁴ so as to allow a single pin to be employed to connect contiguous parts together. Consequently, and in the event of any girder section being damaged or requiring to be removed it can be readily detached and afterwards replaced without interfering with the other sections of the longitudinal girder. Each polygonal section of transverse frame g' are preferably also connected to contiguous polygonal sections by means of pin joints to allow of easy assembly or detachment. H, Figures 1 and 2, is the mesh wiring located between each contiguous pair of gas bags. This mesh wiring has its parts constructed in the manner provided for the purpose described in the co-pending United States application No. 4,161.

It will be observed that by reason of the aforesaid construction internal bracing wires and intermediate frame members are entirely dispensed with.

What I claim and desire to secure by Letters Patent of the United States, is:—

1. A rigid airship provided with transverse frames constituted by built-up space frame girders, each girder comprising a plurality of frame members each of which is built up from ring-like members conforming in shape to the external shape of the airship and each of said ring-like members being itself of space frame or box-like construction.

2. A rigid airship provided with transverse frames constituted by built-up space frame girders, each girder comprising a plurality of frame members each of which is built up from ring-like members conforming in shape to the external shape of the airship and each of said ring-like members being itself of space frame or box-like construction, the parts of each ring-like member of space frame construction being connected together by bracing wires and struts.

3. A rigid airship provided with trans-

verse frames which are of space frame construction and in which the mesh of the wiring which surrounds each gas bag progressively increases from the top to the bottom 5 of the airship.

4. A rigid airship provided with transverse frames which are of triangular or approximately triangular cross section and in which the mesh of the wiring which surrounds each gas bag progressively increases from the top to the bottom of the airship, each wire of the mesh wiring stretching between and having its ends attached to a contiguous pair of transverse frames so that the 10 load is transferred to the frames as a tangential component.

5. A rigid airship in which the longitudinal girders are constructed in sections comprising a strut section which is built into a 20 transverse frame so that its ends project on each side of the frame and an intermediate section located between and having its ends connected to a pair of strut sections.

6. A rigid airship as claimed in claim 5 25 in which each intermediate section of the longitudinal girder is attached at its ends in a detachable manner to the projecting ends of a pair of strut sections.

7. A rigid airship provided with transverse frames which are of box-like formation and between which the contiguous gas bags are located gas valves being provided at the sides of the bag, said valves being arranged to discharge automatically into the 35 trunk-like passage or pipe formed by the box-like transverse frames, the gas which enters the frames from the gas bags being adapted to escape through a hood situated for example at the top of the airship.

40 8. A rigid airship provided with transverse frames which are constituted by built-up space frame girders and in which the mesh of the wiring which surrounds each gas bag progressively increases from the top to the bottom of the airship, each wire of the mesh wiring stretching between and having its ends attached to a contiguous pair of transverse frames so that the load is transferred to the frames as a tangential 45 component, the main loads, such as the passenger cars being located at the sides of the airship where the maximum lifts are obtained.

50 9. A rigid airship as claimed in claim 8

in which corridors or gangways are provided and located along each side of the airship in the space situated between the outer cover of the airship and the inner framework.

55 10. A rigid airship provided with transverse frames which are constituted by built-up space frame girders, and in which the mesh of the wiring which surrounds each gas bag progressively increases from the top to the bottom of the airship, corridors or gangways being provided and located along each side of the airship in the space situated between the outer cover of the airship and the inner framework, said corridors being suspended from catenaries, the ends of each 60 of said catenaries being attached to a contiguous pair of transverse frames.

65 11. A rigid airship provided with transverse frames constituted by built-up space frame girders, each girder comprising a plurality of frame members, each of which is built-up from ring like members conforming in shape to the external shape of the airship and each of said ring like members being itself of space frame construction, staircases being provided and located between the 70 lower portions of said space frame girders.

75 12. A rigid airship having transverse frames constituted by built-up space frame girders, passenger cars located symmetrically on each side of said airship and staircases within said space frame girders establishing communication between said passenger cars.

80 90 13. A rigid airship provided with transverse frames of triangular or approximately triangular cross section, said frames being built up from ring-like members conforming in shape to the external shape of the airship, each of said members being itself of hollow 95 or space-frame construction, said ring-like members being connected together by bracing wires, struts, or the like.

95 100 14. A rigid airship provided with transverse frames of triangular or approximately triangular cross section built up from three ring-like members conforming in shape to the external shape of the airship, each of said members being itself of space frame construction and of triangular cross section 105 and the parts being connected together by bracing wires, struts, or the like.

BARNES NEVILLE WALLIS.
